CLAIM

The ornamental design for a dispenser, as shown and described.

DESCRIPTION

FIG. 1 is an elevated perspective view of a dispenser showing the new design.

FIG. 2 is a front plan view of the dispenser of FIG. 1.

FIG. 3 is a first side plan view of the dispenser of FIG. 1.

FIG. 4 is a second side plan view of the dispenser of FIG. 1.
